UNITED STATES PATENT OFFICE.

BENJAMIN F. HAYDEN, OF SPRINGFIELD, MISSOURI. ASSIGNOR TO HAYDENITE BRICK AND MACHINERY COMPANY, A CORPORATION OF MISSOURI.

BUILDING BLOCK AND WALL.

Application filed September 13, 1922. Serial No. 588,028.

To all whom it may concern:

Be it known that I, BENJAMIN F. HAYDEN, a citizen of the United States, residing at Springfield, in the county of Greene and State of Missouri, have invented a new and useful Building Block and Wall, of which the following is a specification.

The device forming the subject matter of this application is a wall made of bricks or blocks, and the invention aims to provide a structure of the sort above mentioned wherein ordinary rectangular blocks, H-shaped blocks and U-shaped blocks are so combined as to reduce the quantity of material, thereby decreasing the expense of production, shipment and handling, the wall being so constructed that it will stand with a minimum amount of mortar both the inner and outer surfaces of the wall being smooth, the wall being so constituted that the constituent blocks thereof may be laid up readily by a brick layer or mason.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figures 1, 2 and 3, are perspective views showing the various bricks which may be used in the construction of the wall; Figure 4 is a perspective showing a portion of a wall wherein bricks or blocks of all three forms are used; Figure 5 is a longitudinal section of the wall delineated in Figure 4; Figure 6 is a perspective showing a wall made out of the blocks depicted in Figures 1 and 2; Figure 7 is a longitudinal section of the wall shown in Figure 6.

Referring to Figure 1, there is provided a brick or block 1 of common rectangular and oblong form. As disclosed in Figure 2, recourse sometimes is had to a U-shaped block 2 comprising a transverse portion 3

and side arms 4. The device embodies an H-shaped building block 5 comprising parallel side arms 6 and a single connecting portion 7 joining the side arms 6 intermediate their ends, and located at right angles to the side arms 6, the side arms 6 and the connecting portion 7 being of rectangular cross section, the height of the block, measured between the H-shaped surfaces 20 of the block, being approximately equal to the width 21 of either of the side arms 6, thereby to promote stability when the block is laid in a wall with the H-shaped surfaces 20 of the block horizontally disposed. The length 22 of the arms 6 is approximately equal to four times the width 23 of the connecting portion 7, and the distance 24 between the arms 6 being less than twice the width 21 of the arms.

The wall as disclosed in Figure 4 is made up of H-shaped blocks 5 and U-shaped blocks 2 laid in alternating courses, the blocks 1 being disposed at right angles to each other, at a corner of the wall, the blocks 1 co-operating with the courses to dispose the H-shaped and U-shaped blocks of adjoining courses in break joint order and to align the transverse parts 3 of the U-shaped blocks and the transverse parts 7 of the H-shaped blocks vertically.

In Figure 6, the wall is made up of H-shaped blocks 5 laid in alternating courses, and oblong blocks 1 disposed at right angles to each other, at a corner of the wall, the oblong blocks cooperating with the courses to dispose the H-shaped blocks of adjoining courses in break joint order and to dispose the transverse portions 7 of the blocks of superposed courses in alternating order.

What is claimed is:—

A wall made up of H-shaped blocks and U-shaped blocks laid in alternating courses, and oblong blocks disposed at right angles to each other at a corner of the wall, the oblong blocks cooperating with the courses to dispose the H-shaped and U-shaped blocks of adjoining courses in break-joint order and to align the transverse parts of the U-shaped and H-shaped blocks vertically.

In testimony that I claim the foregoing as my own, I have hereto affixed my signature.

BENJAMIN F. HAYDEN.
